UNITED STATES PATENT OFFICE.

ROBERT ANDREW HUTCHISON, JR., OF BRIDGETON, NEW JERSEY.

OIL BURNER.

Application filed June 18, 1925. Serial No. 37,917.

My invention relates to oil burners especially adapted for heating purposes.

The objects are to provide a burner of simple and durable construction which will burn oil without leaving a carbon deposit or causing fluctuations in the flame, and which is practically noiseless.

These objects, and other advantageous ends which will be described hereinafter, I attain in the following manner, reference being had to the accompanying drawings in which

Figure 1 is a central section thru a burner constructed in accordance with my invention illustrating it in the action of burning oil,

Figure 2 a section on line 2—2 of Figure 1,

Figure 3 a side view of the burner looking from the right of Figure 1 showing some of the parts broken away,

Figure 4 a central section thru an element which forms a part of my invention, and

Figure 5 a plan view partly broken away of another element forming a part of my invention.

Referring to the drawings, 1 indicates an air controlling member mounted on a support 2 and secured thereto by angle brackets 3. The air controlling member is in the form of a ring casing 4 cast integral with an oil pan 5 spaced from the inner wall of the casing and connected thereto by integral tie bars 6 spaced around the periphery of the pan. The oil pan has an air conduit 7 extending upwardly to substantially near the top of the casing. Casing 4 is provided with a mortise 8 in which the tenon of a bracket 9 is removably mounted. A gasifying chamber 10, secured to the bracket so as to be disposed substantially centrally above the casing, has an oil inlet pipe 11 connected to its bottom and extending upwardly a short distance into the gasifying chamber as shown at 12. This inlet pipe preferably passes thru the oil pan and is surrounded by a tube 13 to provide a dead-air space 14 around the inlet pipe for heat insulating purposes. The oil passage thru the inlet pipe is restricted by a nipple 15 connected to the lower end of the pipe. This nipple has a small orifice 16 which retards the flow of the oil thru the pipe when a sudden variation of pressure occurs in the gasifying chamber. An oil-feed valve 17 is connected by suitable fittings with nipple 15 and a feed line 18 which is adapted to be connected with a feed tank not shown.

The oil fed into the gasifying chamber thru the inlet pipe 11, is gasified and passes out of the chamber thru an outlet pipe 19 connected with the top of the chamber and preferably diametrically opposite the inlet pipe. The outlet pipe passes downwardly outside of casing 4, then beneath oil pan 5. A nozzle 20 is connected to the outlet pipe and extends upwardly a short distance into air conduit 7. The nozzle is provided with a cleaning rod 21 slidably mounted in the nozzle casing and adapted to be slid into the nozzle to clean the same by a lever 22 fulcrumed to a strip 23 depending from oil pan 5. The oil pan receives its oil for priming the burner thru a pipe 24 connected with feed line 18 by a valve 25 and suitable fittings.

The burner is started by igniting the oil discharged into pan 5 thru pipe 24 and valve 25. This heats the gasifying chamber to a temperature at which the oil will be readily gasified. Oil feed valve 17 is then opened to feed the proper quantity of oil into the gasifying chamber. The oil passes thru the orifice 16 and the inlet pipe 11 into the gasifying chamber and flows onto the hot inner walls of the chamber, where it is gasified and then passes out of the outlet pipe 19 and upwardly thru nozzle 20 against the bottom of the gasifying chamber. The gas issuing from the nozzle becoming ignited by the flame of the oil in the pan, heats the gasifying chamber. The flame impinging against the bottom of the chamber is deflected laterally as shown in Figure 1. The air drawn in thru air conduit 7 and between the casing 4 and pan 5, as shown by the arrows, mixes with the gas and causes complete combustion. The heat produced by the burner is regulated by the amount of oil fed to the gasifying chamber thru valve 17. The maximum amount of oil that may be fed is limited by orifice 16 and this amount will not flood the gasifying chamber or cause it to function improperly while the burner is lit. The temperature of the gasifying chamber at which the burner functions most efficiently is maintained by controlling the combustion of the gasified oil by admission of sufficient air for ignition at the proper point and for complete combustion of the gasified oil after ignition. When this temperature is reached the normal functions of the burner are as follows:

The oil in pipe 11, being insulated from

the hot flame of the burner by tube 13, is heated slightly at this point. Upon reaching the burner the oil becomes hotter. As it passes into the burner to the upwardly projecting end 12 of pipe 11, its temperature is further increased, and as it overflows end 12 and passes down the outer side of pipe 11, it becomes heated to practically the temperature of the gasifying chamber. Upon reaching the hot inner walls of the chamber, it is immediately gasified. The oil is thus gradually heated to its gasifying temperature without danger of decomposing it by sudden heating known as "cracking," and the subsequent formation of carbon resulting from decomposition is avoided.

After the oil is gasified, the gases pass thru outlet pipe 19 and the discharge orifice of nozzle 20 and issue therefrom in a jet which, upon striking the under side of the gasifying chamber, spreads laterally, and the gases having mixed with a quantity of air supplied thru conduit 7, are then ignited, after which they receive a further supply of air thru passage 6, which causes the gases to be completely burned as they flare upwardly around the chamber in a clean white flame.

For best results the size of orifice 16 for feeding oil, and the size of discharge orifice of nozzle 20 for discharging the gasified oil, should be such that a pressure of about $2\frac{3}{4}$ lbs. per square inch is maintained in the gasifying chamber under normal operation of the burner. I have found that by having orifice 16 about .028" in diameter and the nozzle orifice about $7/64$ " in diameter, this pressure is easily maintained.

The temperature of the gasifying chamber at which the burner functions most efficiently is maintained by supplying the gases with just enough air thru conduit 7 to effect ignition after the hot gasified oil strikes the under side of the chamber and then further supplying just enough air thru passage 6 to cause complete combustion of the gasified oil after becoming ignited. Complete combustion is indicated by a clean white flame flaring from under the gasifying chamber without producing an objectionable humming or roaring noise.

A variation of pressure in the gasifying chamber causes the oil in the feed line to oscillate. Nipple 15 with the orifice 16 retard the flow of oil and prevent this oscillation of the oil and the consequent fluctuation in the size of the flame.

The burner functions efficiently and does not cause a carbon deposit as is usual in the ordinary type of burners. It is practically noiseless and requires little attention while burning. The amount of heat produced is easily controlled by valve 17 without harmfully affecting the function of the burner.

While I have described my invention as

taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. An oil burner including a gasifying chamber; an inlet conduit extending part-way into the chamber thru its bottom; an outlet conduit connected to the top of the chamber; a nozzle connected with the outlet conduit; an air conduit around the nozzle for supplying air to the gasified oil to cause ignition thereof after it reaches the chamber; a laterally extending oil pan around the conduit, and a ring casing spaced from the oil pan forming an air passage for supplying air to the ignited gasified oil to cause complete combustion thereof.

2. An oil burner including a gasifying chamber; an inlet conduit extending part-way into the chamber and thru its bottom; an outlet conduit connected with the chamber; a nozzle connected with the outlet conduit for directing the gasified oil against the bottom of the chamber; an air conduit surrounding the nozzle for supplying air to the gasified oil to cause ignition thereof after it reaches the chamber; a laterally extending oil pan around the conduit, the inlet conduit passing thru the oil pan; a tube secured to the bottom of the oil pan and surrounding the inlet conduit between the oil pan and the chamber, and a ring casing spaced from the oil pan to form air passage for supplying air to the gasified oil after becoming ignited.

3. An oil burner including a gasifying chamber; an inlet conduit extending part-way into the chamber and thru its bottom; an outlet conduit connected with the chamber; a nozzle connected with the outlet conduit for directing the gasified oil against the bottom of the chamber; an air conduit surrounding the nozzle for supplying air to the gasified oil to cause ignition thereof after it reaches the chamber; a laterally extending oil pan around the conduit; integral tie bars extending laterally from the pan, and a ring casing integral with the tie bars and spaced from the pan to form an air passage for supplying air to the gasified oil after becoming ignited.

4. In a burner, a ring casing; an oil pan spaced from the casing to form an air passage; tie bars integral with the casing and the oil pan for connecting the pan to the casing; an integral air conduit extending upwardly from the center of the pan; a gasifying chamber; a bracket secured to the casing for supporting the gasifying chamber

above the oil conduit; an inlet conduit passing thru the oil pan and extending into the chamber thru its bottom; a tube secured to the bottom of the pan and surrounding the 5 inlet conduit between the pan and the gasifying chamber; an outlet conduit connected with the chamber, and a nozzle connected

with the outlet conduit for directing the gasified oil thru the air conduit against the bottom of the chamber.

In testimony whereof I have signed my name to this specification.

10
